Henrik J. Schmidt,
Inventor.

UNITED STATES PATENT OFFICE.

HENRIK J. SCHMIDT, OF JACKSONVILLE, FLORIDA, ASSIGNOR TO FLORIDA DEHYDRATING AND PRESERVING CO., OF JACKSONVILLE, FLORIDA, A CORPORATION OF FLORIDA.

DEHYDRATOR.

Application filed December 21, 1923, Serial No. 682,092.

To all whom it may concern:

Be it known that I, HENRIK J. SCHMIDT, a citizen of the United States, residing at Jacksonville, in the county of Duval and the State of Florida, have invented new and useful Improvements in Dehydrators, of which the following is the specification.

My invention relates to an apparatus for dehydrating food-stuffs and other commodities by means of heated air.

While using and operating the dehydrator described and claimed in United States Patent application for improvements in dehydrators, Serial Number 584,456, filed 15 August 26, 1922, of which I am the assignee, I discovered several valuable and useful improvements by which I have greatly added to the efficiency and usefulness of the said dehydrator.

It is well known that in the art of dehydrating organic substances of all kinds the even distribution of the heated air is of the greatest importance, and I have succeeded by the improvements described hereinafter to improve even on the air distribution of the aforementioned dehydrator. I have also been able to affect still further economy in the cost of operating the dehydrator as well as adding to its scope of usefulness.

This and various other improvements and advantages will be clearly understood from the following specification and from the accompanying drawings of a preferred embodiment of my invention, and it will be understood that various modifications might be made without departing from the scope of my invention.

Fig. 1 is a front elevation, showing two units of the dehydrator connected together. One unit is shown with the door closed, and the other unit with the door open, so as to expose the dehydrating chamber.

Fig. 2 is a plan view of Fig. 1.

Fig. 3 is a sectional side elevation of one of the units as indicated by line 3—3 on Fig. 1. Several of the parts having been omitted for the sake of simplicity.

Fig. 4 is a fragmentary front elevation of the apparatus, indicating the travel of the heated air. This view is drawn on a somewhat larger scale than the rest of the views.

Fig. 5 is a perspective view of one of the baffle plates.

In a general way the dehydrator may be said to consist of an outer cabinet having a door in front and provided with air passages on its outer sides. In these air passages, steam heating coils are so placed so as to heat the air as it passes through them. This heated air is then drawn up through the inner air passages, which are located adjacent to the first mentioned passages, and separated from these by thin metal walls. The inner passages have orifices opening into the dehydrating chamber. The air is distributed through these orifices, and by means of baffle plates caused to be drawn evenly through all the trays placed in the dehydrating chamber. After the heated air has passed through the trays it is drawn out through openings formed in the baffle plates and, by means of openings formed in the door and the rear wall of the dehydrating chamber, it is finally drawn into vertical flues placed on the door and rear wall. These flues are, by means of suitable pipes connected with an exhaust fan, which keeps the flow of air constant. Any number of units may be connected together using steam from the same boiler and having their air circulation supplied by the same fan.

I shall now describe the dehydrator in detail, using similar numerals for similar parts on the two units shown.

Referring first to Figs. 1 and 2, each unit consists of a base plate 1, side walls 2, rear wall 3, top plate 4 and front wall 5. The top plate 4 does not extend clear to the side walls 2, but terminates at the points 6, thus forming openings 7 which extend the whole depth of the dehydrator. The door 8 is attached to the front wall 5 by the hinges 9 and is secured in its closed position by the latches 10. For convenience in operation, all the latches are connected to one operating lever 11 so that they may all be operated at one time.

The inner or dehydrating chamber is formed by the base plate 1, top plate 4 and the inner side walls 12. These inner side walls extend the whole depth of the apparatus and from the base plate to the top plate. Between the inner side walls 12 and the outer side walls 2 intermediate side walls 13 are located. These intermediate side walls extend the whole depth of the appa-

ratus, but while, like the inner side walls, they extend to the top plate, they terminate a short distance above the base plate.

Referring now more particularly to Fig.

5 it will be noted that the intermediate side walls 13 are placed at an angle so as to form two tapered passages 14 and 15. The passage 14 is smaller at the lower end while the passage 15 is smaller at the upper end. 10 It will also be noted, as before mentioned, that the intermediate side walls do not extend to the base plate 1, but terminate at the points 16, thus forming a means of communication between the passages 14 and 15. 15 A plurality of wire mesh bottomed trays 17 are placed in the dehydrating chamber. These trays are free to slide in U shaped supports 18 which are securely riveted to the inner side walls 12. Between 20 each of the trays baffle plate 19 are placed and these baffle plates are free to slide on top of the U shaped supports 18. Under each tray and above each baffle plate, with the exception of the uppermost baffle plate, 25 elongated orifices 20 are formed in the inner side walls 12. These orifices extend the whole depth of the apparatus. Immediate above these orifices air guide plates 21 are placed so as to guide the air, drawn up 30 through the passages 15, into the orifices 20. It will be noted that these guide plates are placed at different inclinations so as to distribute the air evenly, but this will be explained later. A steam heating coil 22 is 35 placed in each of the passages 14.

The baffle plates 19, which as already explained are placed between each of the trays and one of which is shown in Fig. 5, are upwardly inclined towards their center 40 axis 23 as plainly shown and are provided with curved plates 24 extending longitudinally parallel with the center axis. These plates are provided with a plurality of perforations 25 which increase in size toward the center. The reason for this will also be explained later.

The door 8 is provided with a plurality of orifices 26 which correspond in number to the number of baffle plates used. These 50 orifices align exactly with the chambers formed in the baffle plates between the uppermost points 23 and the curved plates 24 and are surrounded by flanges 27 which enter a short distance into the said chambers 55 when the door is closed. The rear wall 3 is also provided with similar orifices 28 and have flanges 29 which extend into the baffle plate chambers when the baffle plates are placed in their proper position in the dehydrating chamber. It will again be noted 60 that these orifices, both in the door and rear wall decrease in size upwardly.

The orifices 26 communicate with a tapered flue 30 secured vertically on the door 8, while the orifices 28 communicate with a

similar flue 31 secured on the rear wall 3. Fig. 3 plainly shows these flues as well as the orifices 26 and 28, and flanges 27 and 29. The flue 30 extend some distance above the door 8 and fits tightly over a flue continuation 32, secured on the front wall 5. Both the flues are rounded at their upper ends and connected by means of pipes 33 and 34 to pipe fittings 35 which are connected on the main air exhaust pipe 36. An air 75 exhaust fan, not shown, is connected to this exhaust pipe 36. Dampers 37 and 38 are placed in the pipes 33 and 34 and operated by the lever 39, in the well known manner illustrated.

Steam is supplied to the steam coils 22 through the pipes and pipe fittings 40, 41, 42, 43, 44, 45, 46 and 47. The valves 48 control the steam supply to each dehydrator. The main steam pipe 49 is connected with a boiler, not shown. The condensate from the steam coils flows back to the boiler through the steam return pipe 50 which is connected to the steam coils by the fittings 51 and 52. Valves 53 are connected in the pipe fittings 40 and controls the flow of steam through a perforated pipe 54 connected by means of the pipe 55 and pipe fittings 56. The location of the perforated pipe 54 is shown on Fig. 4 90 but has, for the sake of simplicity, been omitted on the other views.

The openings 7 are covered with fine wire mesh screens, as plainly shown on Fig. 2, and are also provided with hinged shutters 100 57, which when closed completely covers the openings 7.

The dehydrator operates in the following manner:

The material to be dehydrated having 105 been spread on the trays 17, these trays are inserted in the dehydrating chamber and the door 8 is closed. The steam from the boiler enters the steam coils 22 through the pipes and fittings, as already explained. 110 When the fan connected with the exhaust pipe 36 is started a flow of air is drawn through the apparatus.

Cool air is drawn through the openings 7 into the chambers 14 where it is heated by 115 contact with and radiation from the steam coils 22. These coils, extend the whole depth of the chambers 14 and are preferably made in "zig-zag" bends, as shown on Fig. 4, so as to insure the proper heating of the air 120 as it passes. The construction of the chambers 14 and the coils 22 are such that when the air leaves these chambers it is heated to the right temperature. This heated air is now drawn under the edges 16 of the intermediate walls 13 and up into the chamber 15. The tendency of these chambers to become hotter at the top than at the bottom 125 is overcome by the radiation from the thin metal walls 13 into the upper parts of the 130

chambers 14 where the entering air as yet has not had time to be heated. This construction gives an absolute uniform temperature in the chambers 15 and consequently throughout the whole apparatus.

From the chambers 15 the air is drawn in under the trays 17 through the openings 20, which as already explained extend the whole depth of the apparatus. The air 10 guide plates 21, located immediate above each of the openings 20, tend to guide the air into these openings. To secure an equal amount of air passing through each of the trays, the openings 20 decrease in size upwardly, so that the openings farthest from the exhaust fan, or the source of the draft, are the largest. The variation in size of the openings are made by arranging the guide plates 21 at different inclinations. The 15 correct ratio of decrease in the size of the openings having once been found no further regulation of these openings are necessary.

After the air has been drawn through the openings 20, it passes up through the wire mesh in the bottom of each tray, being guided by the tops and bottoms of the baffle plates directly below and above each tray. In passing through the trays the air absorbs the moisture contained in the material deposited on these trays. The air, now saturated with moisture, is next drawn into the chamber, formed under the apex of each baffle plate, through the perforations 25. These perforations are also increased in size 25 as the distance from the fan increases.

From the baffle plate chamber the air is drawn towards the front and the rear of the apparatus and through the orifices 26 and 28 into the flues 30 and 31 from whence it is exhausted through the pipes 33 and 34 into the main exhaust pipe 36. The orifices 26 and 28 are also graduated as to size so that the air is compelled to pass evenly through each orifice. It will be observed that the 30 perforations 25 causes the air to be drawn rectangularly across from the openings 20, thus distributing the air evenly through every part of the trays.

As it is desirable during the first part 35 of the process to use moist air for the drying, the perforated pipes 54 are provided so that water vapors from these pipes mix with the heated air in the chambers 15. The valves 53 regulating the amount of vapor used.

As it is sometimes desirable to steam certain commodities before starting the dehydrating process, the shutters 57 have been provided. When these shutters and the dampers 37 and 38 are closed the apparatus forms a practically steam tight chamber and by opening the valves 53 wide any desired amount of steam may be admitted through the perforated pipes 54.

To any one skilled in the art of dehydra-

tion it will be seen that with this apparatus the steaming or blanching in a separate apparatus is made unnecessary and that by the even distribution of the evenly heated air the curing, now generally resorted to after the materials leave the dehydrator, is avoided.

Having thus described my invention and its operation, what I claim as new and wish to protect by Letters Patent is:

1. In a dehydrating apparatus; downwardly tapering, cold air intake passages located on opposite sides of the apparatus; means for heating the air passing through these passages; upwardly tapering, hot air distributing passages located adjacent to and communicating with the first mentioned passages; the walls separating said cold air and hot air passages constructed of thin metal so as to allow radiation from one passage to another; and the tapers of said passages such that the combination of the tapers with the radiation through the thin metal walls will cause a relatively even temperature of the air through the whole length of the hot air distributing passages.

2. In a dehydrating apparatus; downwardly tapering, cold air intake passages located on opposite sides of the apparatus; means for heating the air passing through these passages; upwardly tapering, hot air distributing passages located adjacent to and communicating with the first mentioned passages; a dehydrating chamber located between the said hot air distributing passages; a plurality of removable trays placed in said dehydrating chamber; baffle plates interposed between each of said trays; the side walls between the dehydrating chamber and the hot air distributing passages provided with a plurality of air inlets; the front and rear walls of the dehydrating chamber provided with a plurality of air outlets; and said air outlets communicating with flues located on the front and rear of the apparatus.

3. In a dehydrating apparatus; downwardly tapering, cold air intake passages located on opposite sides of the apparatus; means for heating the air passing through these passages; upwardly tapering, hot air distributing passages located adjacent to and communicating with the first mentioned passages; a dehydrating chamber located between the said hot air distributing passages; a plurality of removable trays placed in said dehydrating chamber; baffle plates interposed between each of said trays; the side walls between the dehydrating chamber and the hot air distributing passages provided with a plurality of air inlets; the front and rear walls of the dehydrating chamber provided with a plurality of air outlets; said air outlets communicating with flues located on the front and rear of the apparatus.

apparatus; and all of said air inlets and outlets increasing in size from the top to the bottom of the apparatus.

4. In a dehydrating apparatus; downwardly tapering, cold air intake passages located on opposite sides of the apparatus; means for heating the air passing through these passages; upwardly tapering, hot air distributing passages located adjacent to and communicating with the first mentioned passages; a dehydrating chamber located between the said hot air distributing passages; a plurality of removable trays placed in said dehydrating chamber; baffle plates 10 interposed between each of said trays; chambers formed under the apex of each of said baffle plates; a plurality of orifices provided in the bottom plates of said baffle plate chambers; the side walls between the dehydrating chamber and the hot air distributing passages provided with a plurality of air inlets directly under each of 15 said trays; the front and rear walls of the dehydrating chamber provided with a plurality of air outlets; flanges surrounding 20 said air outlets and extending into said

baffle plate chambers; all of said air inlets and outlets increasing in size from the top to the bottom of the apparatus; and all of 25 said baffle plate chamber orifices decreasing in size from the center to the front and rear.

5. In a dehydrating apparatus; a dehydrating chamber; air intake and air distributing passages located on opposite sides 30 of the said dehydrating chamber; flues located at the front and rear of the dehydrating chamber; said flues connected with an exhaust pipe; dampers provided for closing said exhaust pipe; shutters provided for 35 closing the air inlet passages; and perforated pipes located in the air distributing passages whereby the apparatus may be filled with steam.

In testimony whereof, I, HENRIK J. 45 SCHMIDT, have signed this specification in the presence of two subscribing witnesses this 15th day of December, 1923.

HENRIK J. SCHMIDT.
